GAME DEVICE

George C. Boyer, Los Angeles, Calif.

Application November 14, 1933, Serial No. 697,937

20 Claims. (Cl. 273—108)

This invention relates to a game of skill wherein prizes in the form of articles are delivered. The present invention is capable of incorporation in a machine for vending merchandise. Broadly 5 the invention contemplates a prize carrying vehicle which may be moved to impinge against an adjustable target device and on striking the latter will deliver the prize. The vehicle has a substantially fixed path while the target is adjustable to be disposed in the path of the vehicle for engagement by an article delivery mechanism on the vehicle.

It is an object of this invention to provide a device of the character described which may be 15 incorporated in a game simulating well known vehicles and operating in their current manner. In addition to the broader objects of this invention there are certain details of structure enabling the incorporation of the invention in an 20 assemblage inviting in appearance, holding the attention in operation and requiring a degree of skill in operation.

These objects together with other objects and corresponding accomplishments are obtained by 25 means of the embodiment of my invention illustrated in the accompanying drawings, in which:—

Fig. 1 is a front view of a vending machine embodying the game mechanism; Fig. 2 is a section on an enlarged scale as seen on the line 2—2 30 of Fig. 1; Fig. 3 is a section as seen on the line 3—3 of Fig. 2; Fig. 4 is a plan view of a fragment of the vehicle roadway with a vehicle in sectional view; Fig. 5 is a vertical sectional view through a fragment of a vehicle; Fig. 6 is a view as seen on the line 6—6 of Fig. 5; Fig. 7 is a side elevation of 35 the carriage catch; Fig. 8 is a plan view of the carriage catch; Fig. 9 is a sectional view as seen on the line 9—9 of Fig. 8; and Fig. 10 is a section through the target shoe as seen on the line 10—10 40 of Fig. 2.

Referring more particularly to the drawings and especially Fig. 1, the invention is adapted for embodiment in a coin operated vending machine, wherein each time the machine is operated articles will be dispensed and an opportunity afforded to win a prize by skillful manipulation of the game structure. As the vending mechanism forms no part of the present invention, it is not illustrated or described in detail. However, a cabinet A as shown in Fig. 1 may house the vending mechanism and a plurality of game structures indicated by B. A single coin control C is adapted to be moved with its associated mechanism so as to be disposed in coacting relation with any selected game mechanism. The

mechanism enabling this movement will be apparent from the game structure which will now be described in detail.

Each game mechanism A comprises an inclined road or way 11 which is common to all the cars or trucks. There are curbs 12 defining the ways for individual trucks, slots 13 are cut in the road between curbs. At the high end of the road enlarged discharge openings 14 are provided. Vehicles run on the roadways and as shown herein 10 simulate dump trucks. It is obvious however that other vehicles and types of ways may be used. The present disclosure is merely illustrative of one form in which the invention may be embodied. Depending from each vehicle frame is 15 a pusher bar 15 extending through a slot 13. The body 16 of the truck is pivotally mounted and normally urged to slanting position to discharge any article contained therein. On the frame of the vehicle is a spring catch 17 having a keeper 20 end 18 to overlap the upper edge of the front wall of the body and maintain it in non-dumping position. An aperture in the catch 17 receives a striker stem 19, the lower end of the stem being loosely disposed in a pocket on the frame. Thus, 25 an unstable striker is provided for operating the catch to release the body and permit it to dump. On the rear end of the body is a depending apron 20 adapted to enter opening 14 and engage the marginal edge to detain the vehicle 30 while dumping. The openings 14 lead to a prize delivery chute 21. The apron avoids the possibility of strewing the prize articles along the road.

The vehicle actuating mechanism comprises 35 a frame 22 of suitable form having a roller equipped rider 23 at the front embracing a guide rod 24. The guide rod 24 extends along the front of the cabinet A transverse to the path of the vehicles and at a suitable distance below the roadway 11. At the rear of frame 22 is a caster wheel 25 riding on a surface 26 to complete the support for the frame. Mounted at the top of frame 22 is a guide shaft 27 for a carriage 28 to ride thereon. Carriage 28 embraces shaft 27 40 and may be constructed in any suitable manner to have a sliding movement on shaft 27. At the rear upper end of carriage 28 is a hinged pusher plate 29 having a joint which limits swinging movement so that the plate will not swing to the rear past its upright position but may fold to the front. A suitable spring 29' tends to hold plate 29 in its upright position, as shown in Fig. 2. It will be noted that shaft 27 diverges in direction 45 from the roadway so that at the converging end 50 55

plate 29 will overlap pusher 15 and at the diverging end will be disposed out of engagement. Thus, the carriage may be caused to engage the pusher at the low end of the runway. Plate 29 permits the pusher to pass to the rear. By moving the carriage toward the high end, the pusher and vehicle will be moved to the top of the roadway and disengaged so the vehicle may return by gravity to the bottom.

10 In order to cause upward movement of the carriage and vehicle so that the speed of travel of the vehicle may not be manually controlled, I have provided resilient means to cause movement of the truck upwardly. A link 30 is hinged to carriage 28 and fulcrumed at its lower end by having the legs of a slot 30' at the lower end of link 30 straddle a pin 31 on the frame 22.

15 A tension spring 32 is secured at one end to the frame element 22' and connected at the other end to a cable 33 which is passed over a pulley 34. The cable is secured to link 30. This is a convenient means for urging link 30 to the rear and other equivalent means may be substituted therefor. To hold the carriage 28 at the lower end and 20 to release it at will, I have provided a catch mechanism.

25 The catch mechanism is best shown in Figs. 7, 8 and 9 and comprises pivoted latch 35 from which a pin 36 extends laterally. Bearing 30 against the upper face of latch 35 is a leaf spring 37 tending to hold the latch in extended position. Mounted on frame 22 is a trigger mechanism comprising a frame 38. A keeper 39 is fixed to frame 38 and has an upper surface 39a over which the latch pin 36 rides as the carriage is moved to the right hand end of the frame, the latch being swung upwardly against the action of spring 37. When the pin 36 reaches the face 39b, the spring 37 moves the latch 35 35 downwardly so that pin 36 holds the carriage against upward movement. A trigger 40 is pivoted on frame 38 and may overly pin 36. A tension spring 40' tends to hold trigger 40 from contact with pin 36. Secured to the free end 40 of trigger 40 is a chain or cable 41 which is connected to a manually controlled mechanism hereinafter described. By pulling on cable 41, the trigger 40 will be engaged with pin 36 and may move the latter to a position in registration with 45 face 39c of the keeper. This position is maintained against the action of leaf spring 37. The carriage 28 is now released and will move forward by the action of the link 30. In its initial movement and while pin 36 is riding on face 39c, the spring 37 effects a braking action to retard 50 movement of the carriage and vehicle. Too energetic a movement of the carriage at the beginning may displace the vehicle from engagement with the carriage. The braking effect 55 prevents this. On release of the carriage, the vehicle is projected to the high end of the roadway, the curve at the high end checking final movement. At the high end, the plate 29 disengages pusher 15 and the vehicle is freed to return by gravity to the low end of the roadway. The carriage remains at the high end, until it 60 is restored to its low end.

65 To restore the carriage, I have provided a coupling. A slidable bar 42 has a coupling hook 43 pivotally secured to a laterally extending arm on the bar. The hook includes a laterally extending roller 44 journaled on the hook body. A tension spring 45 tends to swing the hook toward link 30, its movement being limited by a 70 stop 67. Depending from the end of hook 43 is

a guide finger 46 disposed to engage a cam 47. Cam 47 has an outer face 47a and an inner face 47b. The cam is fixed to a stem 48 journaled in a bracket on the frame and a spring 49 secured to the stem and frame urges the cam to the position shown in Fig. 3. As the hook is moved toward the left, finger 46 engages face 47a of the cam and the hook is swung out around link 30, then released from the cam to engage the link. By pulling slide 42 toward the right, the link 30 and carriage 28 will be moved to the right and the trigger and catch mechanism engaged to hold the carriage for release by operation of trigger 40. In movement of the hook toward the right, finger 46 engages face 47b of the cam 15 and the latter is turned against the action of spring 49 to clear the finger.

20 The slide 42 is shown associated with a coin control. A frame 50 has a slide way for slide 42 and a finger hold 51 is disposed outside of 25 cabinet A. An aperture 52 admits placing a coin in the coin aperture 53 to slide 42. In the upper face of frame 50 is an opening 54 which the coin aperture may traverse. Pivoted mounted on frame 50 is a lever 55 having a 30 finger 56 in registration with opening 54 and bearing on the slide 42. It will be noted that the finger is inclined on its upper face. If no coin is placed in aperture 53 and the slide is moved inwardly, finger 56 drops into the aperture and prevents movement of the slide to its innermost position or that sufficient for hook 43 to pass cam 47 and engage link 30. If a coin is placed in the aperture, the finger 56 rides over the coin aperture and permits engagement of 35 the hook 43 with link 30 and return of the link and carriage to the vehicle low position. The pawl like mechanism comprising plate 29 and pusher 15 enables the plate to pass in front of the pusher. Carriage 28 is then held by the catch 40 mechanism. Cable 41 is secured to lever 55 so that when the lever is pulled down the trigger 40 is tripped to release the carriage. Below the frame 50 is a coin receiver 57 whose mouth is located inwardly of finger 56. A coin dislodger 45 wheel 58 insures the coin being dropped into receiver 57 when located thereover. The insertion of a coin enables the slide to be moved so that hook 43 engages link 30. On return of the 50 slide, finger 56 drops into the coin aperture 53 and rides thereover allowing the slide to be withdrawn to its full extent. If the slide is now pushed inwardly, finger 56 drops into aperture 53 and the marginal edge of the latter presses the finger and lever 55 downwardly causes tripping of the catch and release of carriage 28. This causes projection of the vehicle to the top of the roadway and its release.

55 The vehicle body 16 is charged with an article to be dumped, and dumping is obtained by operating striker 19. A channel bar 59 extends across the cabinet A transverse to the path of travel of the vehicles. Below the channel is a guide rod 60 and slidably mounted on the rod is a target 61. The target is mounted so that it may 60 rock on the rod in a pendulous manner. A finger 62 on the target is disposed to engage a leg of the channel bar to limit its swinging movement toward the rear. Depending from the target is a stem carrying a leaf spring 63 forming a resilient 70 stem and on the end of a stem is a target shoe 64 of torpedo shape. Target 61 is moved by cables 65 forming an endless belt with the target therein. The belt is passed over guide pulleys and moved by an operating roller 66 having a suitable hand 75

wheel outside the cabinet. If target shoe 64 is positioned to be squarely struck by striker 19, the truck will be dumped.

The trucks are filled with the prize articles.

- 5 A player selects a truck and slides the coin device 51 and thereby the vehicle operating mechanism to a position corresponding with the selected truck. The player then adjusts the target 61 so that in his opinion it is in line with the truck 10 and that it will be struck by the striker 19, he then inserts a coin in the coin slide 51 and pushes the latter fully in. This causes the coupling hook 43 to engage link 30. The slide is thereafter fully retracted to cause carriage 28 to engage the selected vehicle. Further adjustment of the target 15 shoe 64 may then be made if desired. Next the player pushes the slide in causing the carriage to be released and the vehicle is then projected along the roadway 11 toward the target shoe 64. 20 The unstable striker 19 adds to the skill required to trip the dump body 16. The target shoe 64 also adds to the skill required because of its shape. If a strike is made the vehicle is dumped so that the articles fall into chute 21 and are delivered. 25 The empty truck will remain at the top by reason of apron 20 engaging and holding on the edge of opening 14. If no strike is made, the released truck returns with its load for further operation. It is to be understood that while the terms "truck" 30 and "vehicle" have been used as referring to the device within which articles are carried that the invention is not limited to such specific structures but to any element, receptacle, or vehicle by which the prizes may be conveyed.

35 What I claim is:—

1. A game device comprising a travelling article carrying body provided with dumping means to discharge articles carried thereby, a trip to control dumping of said member, guide means to constrain said member to a preselected path; manually controllable means to cause said member to travel; a target mechanism transversely movable with relation to the path of travel of said vehicle, manually controllable adjustment means 40 to move said target and selectively adjust the position of the latter, whereby the engagement of the trip with the target will effect the dumping of the carrying member.

2. A game device comprising a travelling article carrying member provided with dumping means to discharge articles carried thereby, a trip to control dumping of said carrying member, guide means to constrain said carrying member to a preselected path; manually controllable means to cause said carrying member to travel, means tending to move said carrying member along its path of travel, a trigger to hold said carrying member against movement at an end of said path, a catch for engagement by said trigger to hold 45 said carrying member normally at said end of its path, means connecting said manually controllable means and said trigger to effect release of said catch on initial movement of said manually controllable means away from said end of its path; a target mechanism including a member transversely movable with relation to the path of travel of said vehicle, manually controllable adjustment means to move said member and selectively adjust 50 the position of the latter, a target on said member for positioning in a path to register with said trip whereby said member may be adjustably positioned to be engaged by said trip and effect dumping of said vertical carrying member.

- 75 3. A game device comprising a travelling ve-

hicle having an article carrying body provided with dumping means to discharge articles carried thereby, a trip to control dumping of said vehicle, guide means to constrain said vehicle to a preselected path; a travelling carriage for engagement with said vehicle to cause the latter to travel, manually controllable means to move said carriage; a target mechanism including a target body transversely movable with relation to the path of travel of said vehicle, manually controllable adjustment means to move said target body and selectively adjust the position of the latter, a target member on said target body for positioning in the path of said trip whereby said target member may be adjustably positioned to be engaged by said trip and effect dumping of said vehicle.

4. A game device comprising a travelling vehicle having an article carrying body provided with dumping means to discharge articles carried thereby, an unstable trip to control dumping of said vehicle, guide means to constrain said vehicle to a preselected path; a travelling carriage for engagement with said vehicle to move the latter to one end of its path of travel, resilient means tending to move said carriage to the other end of its path of travel, manually controllable means to move said carriage against the action of said resilient means, a trigger at said other end of said path, a catch on said carriage 20 for engagement by said trigger to hold said carriage, means connecting said manually controllable means and said trigger to effect release of said catch on initial movement of said manually controllable means from said other end of said path; a target mechanism including a target body transversely movable with relation to the path of travel of said vehicle, manually controllable adjustment means to move said target body and selectively adjust the position of the latter, 25 a target member on said target body for positioning in the path of said trip whereby said target member may be adjustably positioned to be engaged by said trip and effect dumping of said vehicle.

5. A game device comprising a travelling vehicle having an article carrying body provided with dumping means to discharge articles carried thereby, a trip to control dumping of said vehicle, guide means to constrain said vehicle to a preselected path, a pusher member depending from said vehicle; a travelling carriage having an abutment member to engage said pusher member, guide means for said carriage ranging in the direction of travel of said vehicle so that 30 said abutment member will engage said pusher member at one end of said path and disengage it at the other end whereby to release said vehicle, resilient means tending to move said carriage to one end of its path of travel, manually controllable means to move said carriage against the action of said resilient means, a trigger at the other end of said path, a catch on said carriage 35 for engagement by said trigger to hold said carriage at said other end, means connecting said manually controllable means and said trigger to effect release of said catch on initial movement of said manually controllable means from said other end; a target mechanism including a target body transversely movable with relation to the path of travel of said vehicle, manually controllable adjustment means to move said target body and selectively adjust the position of the latter, a target member on said target body for 40 positioning in the path of said trip whereby said

target member may be adjustably positioned to be engaged by said trip and effect dumping of said vehicle.

6. A game device comprising a travelling vehicle simulating a dump truck, said vehicle having an article carrying dump body tending to maintain itself in dumping position to discharge articles contained therein, a trip latch to hold said body in non-dumping position, an unstable 10 striker upstanding from said latch for operating the latter to release said body, a way on which said vehicle travels, a pusher member depending from said vehicle; a travelling carriage having an abutment member to engage said pusher member, guide means for said carriage ranging in the direction of travel of said vehicle so that said abutment member will engage said pusher member at one end of said way and disengage it at the other end whereby to release 20 said vehicle, resilient means tending to move said carriage to one end of its path of travel, manually controllable means to move said carriage against the action of said resilient means, a trigger at the other end of said path, a catch on said 25 carriage for engagement by said trigger to hold said carriage at said other end, means to check initial movement of said carriage when released, means connecting said manually controllable means and said trigger to effect release of said 30 catch on initial movement of said manually controllable means away from said other end; a target mechanism including a target body transversely movable with relation to the path of travel of said vehicle, manually controllable adjustment 35 means to move said target body and selectively adjust the position of the latter, a target member on said target body for positioning in the path of said striker whereby said target member may be adjustably positioned to be engaged by said 40 striker and effect dumping of said dump body.

7. A game device comprising a travelling vehicle simulating a dump truck, said vehicle having an article carrying dump body tending to maintain itself in dumping position to discharge 45 articles contained therein, a trip latch to hold said body in non-dumping position, a striker upstanding from said latch for operating the latter to release said body, a way on which said vehicle travels, a pusher member depending from 50 said vehicle; a travelling carriage having an abutment member to engage said pusher member, guide means for said carriage ranging in the direction of travel of said vehicle so that said abutment member will engage said pusher member at one end of said way and disengage it at the other end whereby to release said vehicle, resilient means tending to move said carriage to one end of its path of travel, manually 55 controllable means to move said carriage against the action of said resilient means, a trigger at the other end of said path, a catch on said carriage for engagement by said trigger to hold said carriage at said other end, means to check initial movement of said carriage when released, 60 means connecting said manually controllable means and said trigger to effect release of said catch on initial movement of said manually controllable means from said other end; a target mechanism including a target body transversely 65 movable with relation to the path of travel of said vehicle, manually controllable adjustment means to move said target body and selectively adjust the position of the latter, a resilient stem depending from said target body having a target 70 member for positioning in the path of said 75

striker whereby said target member may be positioned to be engaged by said striker and effect dumping of said dump body, said member being mounted to have a limited pendulous movement in the direction of travel of said vehicle.

8. A game device comprising a travelling vehicle simulating a dump truck, said vehicle having an article carrying dump body tending to maintain itself in dumping position to discharge articles contained therein, a trip latch to hold 10 said body in non-dumping position, a striker upstanding from said latch for operating the latter to release said body, a way on which said vehicle travels, a pusher member depending from 15 said vehicle; a travelling carriage having an abutment member to engage said pusher member, guide means for said carriage ranging in the direction of travel of said vehicle so that said abutment member will engage said pusher member at one end of said way and disengage it 20 at the other end whereby to release said vehicle, resilient means tending to move said carriage to one end of its path of travel, manually controllable means to move said carriage against the action of said resilient means, a trigger at the 25 other end of said path, a catch on said carriage for engagement by said trigger to hold said carriage, means connecting said manually controllable means and said trigger to effect release of said 30 catch on initial movement of said manually controllable means from said other end of said path; a target mechanism including a target body transversely movable with relation to the path of travel of said vehicle, manually controllable adjustment 35 means to move said target body and selectively adjust the position of the latter, a resilient stem depending from said target body having a target member for positioning in registration with said striker whereby said target member may be positioned to be engaged by said 40 striker as it moves with the truck and effect dumping of said truck body, said target member being mounted to have a limited pendulous movement in the direction of travel of said vehicle.

9. A game device comprising a travelling vehicle simulating a dump truck, said vehicle having an article carrying dump body tending to maintain itself in dumping position to discharge articles contained therein, a trip latch to hold 45 said body in non-dumping position, an unstable 50 striker upstanding from said latch for operating the latter to release said body, a way on which said vehicle travels, a pusher member depending from said vehicle; a travelling carriage having an abutment member to engage said pusher member, guide means for said carriage ranging in the direction of travel of said vehicle so that said abutment member will engage said pusher member at one end of said way and disengage it 55 at the other end whereby to release said vehicle, resilient means tending to move said carriage to one end of its path of travel, manually controllable means to move said carriage against the action of said resilient means, a trigger at the other end of said path, a catch on said carriage 60 for engagement by said trigger to hold said carriage, means connecting said manually controllable means and said trigger to effect release of said catch on initial movement of said manually controllable means from said other end of its path; a target mechanism including a target body transversely movable with relation to the path of travel of said vehicle, manually 65 controllable adjustment means to move said target body and selectively adjust the position of the 70 target body and selectively adjust the position of the 75

latter, a resilient target member depending from said target body for positioning in the path of and in registration with said striker whereby said target member may be positioned to be encountered by said striker as the truck moves and effect dumping of said truck body.

10. A game device comprising a travelling vehicle simulating a dump truck, said vehicle having an article carrying dump body tending to maintain itself in dumping position to discharge articles contained therein, a trip latch to hold said body in non-dumping position, an unstable striker upstanding from said latch for operating the latter to release said body, an inclined way 15 on which said vehicle travels, a pusher member depending from said vehicle; a travelling carriage below said way having an abutment member to engage said pusher member, guide means for said carriage ranging in and diverging from the direction of travel of said vehicle so that said abutment member will engage said pusher member in overlapping relation at the low end of said way and disengage at the high end whereby to release said vehicle, said pusher and abutment 20 members comprising a pawl like mechanism, resilient means tending to move said carriage toward the high end of said way; a manually operable slide, a coupling connected to said slide to enable movement of said carriage to the low end, a trigger, a catch on said carriage for engagement by said trigger at low end position of said carriage to hold the latter, means to check initial movement of said carriage when released, means connecting said slide and trigger to effect 25 release of said catch on initial movement of said slide away from the low vehicle position; a target mechanism including a target body transversely movable with relation to the path of travel of said vehicle, manually operable means to move said target body and selectively position the latter, and a target member on said target body for positioning in the path of said striker whereby said target member may be positioned to be engaged by said striker and effect 30 dumping of said truck body.

11. A game device comprising a travelling vehicle simulating a dump truck, said vehicle having an article carrying dump body tending to maintain itself in dumping position to discharge articles contained therein, a trip latch to hold said body in non-dumping position, a striker upstanding from said latch for operating the latter to release said body, an inclined way on which said vehicle travels, a pusher member depending from said vehicle; a travelling carriage below said way having an abutment member to engage said pusher member, guide means for said carriage ranging in and diverging from the direction of travel of said vehicle so that said abutment member will engage said pusher member in overlapping relation at the low end of said way and disengage at the high end whereby to release said vehicle, said pusher and abutment members comprising a pawl like mechanism, resilient means tending to move said carriage toward the high end of said way; a manually operable slide, a coupling connected to said slide to enable movement of said carriage to the low end, a trigger, a catch on said carriage for engagement by said trigger at low end position of said carriage to hold the latter, means to check initial movement of said carriage when released, means connecting said slide and trigger to effect 40 release of said catch on initial movement of said slide away from the low vehicle position; a target mechanism including a target body transversely movable with relation to the path of travel of said vehicle, manually operable means to move said target body and selectively position the latter, a resilient target member depending from said target body for positioning in the path of said striker whereby said target member may be positioned to be engaged by said striker and effect dumping of said truck body.

12. A game device comprising a travelling vehicle simulating a dump truck, said vehicle having an article carrying dump body tending to maintain itself in dumping position to discharge articles contained therein, a trip latch to hold said body in non-dumping position, a striker upstanding from said latch for operating the latter to release said body, an inclined way on which said vehicle travels, a pusher member depending from said vehicle; a travelling carriage below said way having an abutment member to engage said pusher member, guide means for said carriage ranging in and diverging from the direction of travel of said vehicle so that said abutment member will engage said pusher member in overlapping relation at the low end of said way and disengage at the high end whereby to release said vehicle, said pusher and abutment members comprising a pawl like mechanism, resilient means tending to move said carriage toward the high end of said way; a manually operable slide, a coupling connected to said slide to enable movement of said carriage to the low end, a trigger, a catch on said carriage for engagement by said trigger at low end position of said carriage to hold the latter, means to check initial movement of said carriage when released, means connecting said slide and trigger to effect release of said catch on initial movement of said slide away from the low vehicle position; a target mechanism including a target body transversely movable with relation to the path of travel of said vehicle, manually operable means to move said target body and selectively position the latter, and a target member on said target body for positioning in registration with said striker whereby said target member may be positioned to be engaged by said striker and effect dumping of said truck body, said target member being mounted to have a limited pendulous movement in the direction of travel of said vehicle.

13. A game device comprising a travelling vehicle simulating a dump truck, said vehicle having an article carrying dump body tending to maintain itself in dumping position to discharge articles contained therein, a trip latch to hold said body in non-dumping position, an unstable striker upstanding from said latch for operating the latter to release said body, an inclined way on which said vehicle travels, a pusher member depending from said vehicle; a travelling carriage below said way having an abutment member to engage said pusher member, guide means for said carriage ranging in and diverging from the direction of travel of said vehicle so that said abutment member will engage said pusher member in overlapping relation at the low end of said way and disengage at the high end whereby to release said vehicle, said pusher and abutment members comprising a pawl like mechanism, resilient means tending to move said carriage toward the high end of said way; a manually operable slide, a coupling connected to said slide to enable movement of said carriage to the low end, a trigger, a catch on said carriage for engagement by said trigger at low end position of said carriage to hold the latter, means to check initial movement of said carriage when released, means connecting said slide and trigger to effect release of said catch on initial movement of said slide away from the low vehicle position; a target mechanism including a target body transversely movable with relation to the path of travel of said vehicle, manually operable means to move said target body and selectively position the latter, and a target member on said target body for positioning in registration with said striker whereby said target member may be positioned to be engaged by said striker and effect dumping of said truck body, said target member being mounted to have a limited pendulous movement in the direction of travel of said vehicle.

carriage for engagement by said trigger at low end position of said carriage to hold the latter, means connecting said slide and trigger to effect release of said catch on initial movement 5 of said slide away from the low vehicle position; a target mechanism including a target body transversely movable with relation to the path of travel of said vehicle, manually operable means to move said target body and selectively 10 position the latter, resilient target member depending from said target body for positioning in the path of said striker whereby said target member may be positioned to be engaged by said striker and effect dumping of said truck body, 15 said member being mounted to have a limited pendulous movement in the direction of travel of said vehicle.

14. A game device comprising a travelling vehicle simulating a dump truck, said vehicle having an article carrying dump body tending to maintain itself in dumping position to discharge articles contained therein, a trip latch to hold said body in non-dumping position, an unstable striker upstanding from said latch for operating 20 the latter to release said body, an inclined way on which said vehicle travels, a pusher member depending from said vehicle; a travelling carriage below said way having an abutment member to engage said pusher member, guide means 25 for said carriage ranging in and diverging from the direction of travel of said vehicle so that said abutment member will engage said pusher member in overlapping relation at the low end of said way and disengage at the high end 30 whereby to release said vehicle, said pusher and abutment members comprising a pawl like mechanism, a spring means tending to move said carriage toward the high end of said way; a manually operable slide, a coupling connected to 35 said slide to enable movement of said carriage to the low end, a trigger, a catch on said carriage for engagement by said trigger at low end position of said carriage and to hold the latter, means to check initial movement of said carriage when released, means connecting said slide and trigger to effect release of said catch on initial movement of said slide away from the vehicle position; a target mechanism including a target body transversely movable with relation to the path of travel of said vehicle, manually operable means to move said target body and selectively position the latter, a resilient target member depending from said target body for positioning in registration with said striker whereby said target member may be positioned to be engaged by said striker and effect dumping of said truck body, 40 said target member being mounted to have a limited pendulous movement in the direction of travel of said vehicle.

16. A game device comprising travelling vehicle simulating a dump truck, said vehicle having an article carrying dump body tending to maintain itself in dumping position to discharge articles contained therein, a trip latch on said vehicle to hold said body in non-dumping position, an unstable striker upstanding from said latch for operating the latter to release said body, an inclined way on which said vehicle travels, a pusher member depending from said vehicle; a travelling carriage below said way having an abutment member to engage said pusher member, guide means for said carriage ranging in and diverging from the direction of travel of said vehicle so that said abutment member will engage said pusher member in overlapping relation at the low end of said way and disengage at the high end whereby to release said vehicle, said pusher and abutment members comprising a pawl like mechanism, link means urging movement of said carriage toward the high end of said way; a manually operable slide, a coupling connected to said slide to engage said link means and enable movement thereof and carriage to the low end, a trigger, a catch on said carriage for engagement by said trigger at low end position of said carriage to hold the latter, means connecting said slide and trigger to effect release of said catch on initial movement of said slide away from the vehicle position; a target mechanism including a target body transversely movable with relation to the path of travel of said vehicle, manually operable means to move said target body and selectively position the latter, a resilient target member depending from said target body for positioning in registration with said striker whereby said target member may be positioned to be engaged by said striker and effect dumping of said truck body.

15. A game device comprising a travelling vehicle simulating a dump truck, said vehicle having an article carrying dump body tending to maintain itself in dumping position to discharge articles contained therein, a trip latch to hold said body in non-dumping position, a striker upstanding from said latch for operating the latter to release said body, an inclined way on which said vehicle travels, a pusher member depending from said vehicle; a travelling carriage below said way having an abutment member to engage said pusher member, guide means for said carriage ranging in and diverging from the direction of travel of said vehicle so that said abutment member will engage said pusher member in overlapping relation at the low end of said way and disengage at the high end whereby to release said vehicle, said pusher and abutment

members comprising a pawl like mechanism; a spring means tending to move said carriage toward the high end of said way; a manually operable slide, a coupling connected to said slide to enable movement of said carriage to the low end, a trigger, a catch on said carriage for engagement by said trigger at low end position of said carriage to hold the latter, means to check initial movement of said carriage when released, means connecting said slide and trigger to effect release of said catch on initial movement of said slide away from the low vehicle position; a target mechanism including a target body transversely movable with relation to the path of travel of said vehicle, manually operable means to move said target body and selectively position the latter, a resilient target member depending from said target body for positioning in registration with said striker whereby said target member may be positioned to be engaged by said striker and effect dumping of said truck body, said target member being mounted to have a limited pendulous movement in the direction of travel of said vehicle.

17. A game device comprising a travelling vehicle simulating a dump truck, said vehicle having an article carrying dump body tending to maintain itself in dumping position to discharge articles contained therein, a trip latch on said vehicle to hold said body in non-dumping position, a striker upstanding from said latch for operating the latter to release said body, an inclined way on which said vehicle travels, a pusher member depending from said vehicle; a travelling carriage below said way having an abutment member to engage said pusher member, guide means for said carriage ranging in and diverging from the direction of travel of said vehicle so that said abutment member will engage said pusher member in overlapping relation at the low end of said way and disengage at the high end whereby to release said vehicle, said pusher and abutment members comprising a pawl like mechanism, link means urging movement of said carriage toward the high end of said way; a manually operable slide, a coupling connected to said slide to engage said link means and enable movement thereof and carriage to the low end, a trigger, a catch on said carriage for engagement by said trigger at low end position of said carriage to hold the latter, means connecting said slide and trigger to effect release of said catch on initial movement of said slide away from the vehicle position; a target mechanism including a target body transversely movable with relation to the path of travel of said vehicle, manually operable means to move said target body and selectively position the latter, a resilient target member depending from said target body for positioning in registration with said striker whereby said target member may be positioned to be engaged by said striker and effect dumping of said truck body.

- ranging in and diverging from the direction of travel of said vehicle so that said abutment member will engage said pusher member in overlapping relation at the low end of said way and disengage at the high end whereby to release said vehicle, said pusher and abutment members comprising a pawl like mechanism, a spring urged link tending to move said carriage toward the high end of said way; a manually operable slide, a coupling connected to said slide to engage said link and enable movement of said link and carriage to the low end, a trigger, a catch on said carriage for engagement by said trigger at low end position of said carriage and to hold the latter, means connecting said slide and trigger to effect release of said catch on initial movement of said slide away from the low vehicle position; a target mechanism including a target body transversely movable with relation to the path of travel of said vehicle, manually operable means to move said target body and selectively position the latter, a resilient target member depending from said target body for positioning in registration with said striker whereby said target member may be positioned to be engaged by said striker and effect dumping of said truck body, said target member being mounted to have a limited pendulous movement in the direction of travel of said vehicle.
18. A game device comprising a travelling vehicle simulating a dump truck, said vehicle having an article carrying dump body tending to maintain itself in dumping position to discharge articles contained therein, a trip latch on said vehicle to hold said body in non-dumping position, an unstable striker upstanding from said latch for operating the latter to release said body, an inclined way on which said vehicle travels, a pusher member depending from said vehicle; a travelling carriage below said way having an abutment member to engage said pusher member, guide means for said carriage ranging in and diverging from the direction of travel of said vehicle so that said abutment member will engage said pusher member in overlapping relation at the low end of said way and disengage at the high end whereby to release said vehicle, said pusher and abutment members comprising a pawl like mechanism, a spring urged link tending to move said carriage toward the high end of said way; a manually operable slide, a coupling connected to said slide to engage said link and enable movement of said link and carriage to the low end, a trigger, a catch for engagement by said trigger on said carriage at low end position of said carriage and to hold the latter, means to check initial movement of said carriage when released, means connecting said slide and trigger to effect release of said catch on initial movement of said slide away from the low vehicle position; a target mechanism including a target body transversely movable with relation to the path of travel of said vehicle, manually operable means to move said target body and selectively position the latter, a resilient target member depending from said target body for positioning in registration with said striker whereby said target member may be positioned to be engaged by said striker and effect dumping of said body, said target member being mounted to have a limited pendulous movement in the direction of travel of said vehicle.
19. A game device comprising a travelling vehicle simulating a dump truck, said vehicle having an article carrying dump body tending to maintain itself in dumping position to discharge articles contained therein, a trip latch on said vehicle to hold said body in non-dumping position, an unstable striker upstanding from said latch for operating the latter to release said body, an inclined way on which said vehicle travels, a pusher member depending from said vehicle; a travelling carriage below said way having an abutment member to engage said pusher member, guide means for said carriage ranging in and diverging from the direction of travel of said vehicle so that said abutment member will engage said pusher member in overlapping relation at the low end of said way and disengage at the high end whereby to release said vehicle, said pusher and abutment members comprising a pawl like mechanism, a spring urged link tending to move said carriage toward the high end of said way; a manually operable slide, a coupling connected to said slide to engage said link and enable movement of said link and carriage to the low end, a trigger, a catch for engagement by said trigger on said carriage at low end position of said carriage and to hold the latter, means to check initial movement of said carriage when released, means connecting said slide and trigger to effect release of said catch on initial movement of said slide away from the low vehicle position; a target mechanism including a target body transversely movable with relation to the path of travel of said vehicle, manually operable means to move said target body and selectively position the latter, a resilient target member depending from said target body for positioning in registration with said striker whereby said target member may be positioned to be engaged by said striker and effect dumping of said body, said target member being mounted to have a limited pendulous movement in the direction of travel of said vehicle.
20. A game device comprising a traveling member provided with means to discharge articles carried thereby, means to constrain said traveling member to a definite path of travel, means for causing said traveling member to move along said path of travel, a trip member carried by the traveling member and moving therewith, a target adapted to be selectively positioned in the path of travel of the trip member, and whereby the trip member will be actuated to discharge articles from the traveling member when the trip member encounters the target.

GEORGE C. BOYER.
